CLAIM

The ornamental design for a cassette with insert trays for storage of surgical instruments and auxiliaries, as shown and described.

DESCRIPTION

1. Cassette with insert trays for storage of surgical instruments and auxiliaries

1.1 : Front

1.2 : Back

1.3 : Top

1.4 : Bottom

1.5 : Left

1.6 : Right

1.7 : Unfolded

1.8 : Exploded

1.9 : Perspective

1.10 : Unfolded detail perspective view

1.11 : Detail top view

1.12 : Detail top perspective view

1.13 : Detail bottom perspective view

1.14 : Detail top view

1.15 : Detail top perspective view

1.16 : Detail bottom perspective view

1.17 : Detail bottom view

1.18 : Detail top perspective view

1.19 : Detail bottom perspective view

1.20 : Detail bottom view

1.21 : Detail top perspective view

1.22 : Detail bottom perspective view

A modular box with several insert trays for dental instruments and implants.

(Continued)

In the reproductions, the broken lines show portions of a cassette with insert trays for storage of surgical instruments and auxiliaries that form no part of the claim.
